UNITED STATES PATENT OFFICE.

CLIDA CHAPMAN, OF CHERRYVALE, KANSAS.

WASHING-MACHINE.

1,312,831.

Specification of Letters Patent. Patented Aug. 12, 1919.

Application filed January 10, 1918. Serial No. 211,161.

To all whom it may concern:

Be it known that I, CLIDA CHAPMAN, a citizen of the United States, residing at Cherryvale, in the State of Kansas, have invented a new and useful Washing-Machine; and I do hereby declare the following to be a full, clear, and exact description of the invention, such as will enable others skilled in the art to which it appertains to make and use the same.

This invention relates to an improved washing machine.

One of the objects of the invention is to provide a simple, efficient and practical machine of this kind in which is used an efficient and practical agitator.

A further object of the invention is to provide an improved, simple and practical agitator, and movable agitating fingers or projections therefor.

A further object of the invention is to provide an improved supporting stand for the receptacle.

In practical fields the details of construction may necessitate alterations falling within the scope of what is claimed.

The invention comprises further features and combination of parts as hereinafter set forth shown in the drawings and claimed.

30 In the drawings:

Figure 1 is a view in side elevation of the improved washing machine constructed in accordance with the invention.

35 Fig. 2 is a vertical sectional view through the same.

Fig. 3 is a horizontal sectional view on line 3—3 of Fig. 1.

40 Fig. 4 is an enlarged detail sectional view of the body part of the agitator, showing the mounting of the agitating fingers.

Referring more especially to the drawings 1 designates a clothes and suds receiving receptacle, which is constructed from a piece of corrugated sheet metal. The sheet metal 45 is bent whereby the corrugations 2 may extend perpendicularly of the sides of the receptacle. The corrugations 3 of the bottom of the receptacle extend from one side of the receptacle to the opposite side, as shown 50 clearly in the plan view of Fig. 3. This sheet metal of the receptacle may be galvanized, and secured to and projecting inwardly from the upper marginal edge of the receptacle is a flange 4, the screws 5 acting to hold the 55 same in place. A suitable closure 6 fits into the opening 7 and has a marginal flange 8

resting upon the flange 4. A supporting frame 9 comprising the four legs 10, which are reinforced by the braces 11, is provided. The upper ends of the legs 10 terminate in 60 angular parts 12, which receive and are secured in any suitable manner to the receptacle engaging frame 13, which is angular in cross section as clearly illustrated. A vertical shaft 14 is mounted in a bearing 15 of 65 the closure 6, there being collars 16 riveted to the shaft 14 above and below the closure to prevent vertical axial movement of said shaft. The upper end of the shaft has secured thereto by means of the screw 17 a 70 handle 18, by the oscillation of which, the vertical shaft 14 may be rocked. The lower end of the shaft is provided with an extension 20, which is rectangular in cross section, and the extremity of the extension terminates in 75 a reduced cylindrical part 21. An agitator is provided on the shaft 14. For instance the body of the agitator is mounted upon the extension 20, and consists of the sections 23, 24 and 25. The sections 22 and 23, 80 (which are constructed of wood) are secured together by the wood screws 26. The adjacent faces of the sections 22 and 23 are provided with semi-spherical cavities 27, which when the sections 22 and 23 are secured together, form spherical bearings for the spherical enlargements 28 of the agitating fingers 29, which extend radially from the body of the agitator. The sections 22 and 85 23 have their adjacent faces where the fingers 29 project from therebetween, provided with tapered openings 30, so that when a rocking movement is imparted to the body of the agitator, said agitating fingers are 90 allowed to move independently of the body and independently of each other, so as to more effectively insure a crushing and scrubbing action on the clothes, as the agitating fingers coöperate with the corrugations of the sides, to remove the dirt from the clothes. 95 It is to be observed that the section 25 of the body is mounted to movably rock on the reduced cylindrical part 21 of said extension 20. In other words the section 25 is mounted, whereby the sections 23 and 24 as one 100 body may move independently of the section 25. A washer 31 and a nut 32 which is threaded on a reduced part of the portion 21, hold the section 25 of the agitator in place. Agitating fingers 33 are carried by 105 the section 25. These fingers 33 extend downwardly and radially from the section

25, and act to coöperate with the corrugations of the bottom of the receptacle 1, to assist in removing the dirt from the clothes. The section 25 has a segmental slot 34, and 5 a pin 35 carried by and projecting from the section 24 extends into the slot 34, so as to co-operate with the opposite ends of said slot and limit the sections 23 and 24 in their rocking movements together with relation 10 to and independently of the section 25, and the agitator is operated to remove the dirt from the clothes.

The invention having been set forth what is claimed as new and useful is:—

- 15 An agitator for a washing machine comprising a shaft, a body member at the lower end thereof, said body member comprising two sections having semi-spherical recesses therein forming spherical bearings having 20 tapering openings extending radially therefrom and in a horizontal plane, each section

having a square aperture, said apertures being adapted to be received by the squared end of the lower end of the shaft, said apertures when registered with each other will 25 cause the registration of the semi-spherical recesses and tapering openings of the sections, agitator fingers provided with spherical enlargements, said enlargements being disposed in the spherical bearings formed by 30 the semi-spherical recesses and extending radially from said body member and means passing through the sections for securely securing them together.

In testimony whereof I have signed my 35 name to this specification in the presence of two subscribing witnesses.

CLIDA CHAPMAN.
